UNITED STATES PATENT OFFICE.

EMRO HARCHARICK, OF WILKES-BARRE, PENNSYLVANIA.

FUEL-FEEDING DEVICE.

No. 824,356.

Specification of Letters Patent.

Patented June 26, 1906.

Application filed August 9, 1904. Serial No. 220,113.

To all whom it may concern:

Be it known that I, EMRO HARCHARICK, a citizen of the United States, residing at Wilkes-Barre, in the county of Luzerne, State of Pennsylvania, have invented certain new and useful Improvements in Fuel-Feeding Devices, of which the following is a specification.

This invention relates to fuel-feeding devices or stokers, and has for its object the provision of improvements in this class of apparatus, as will be hereinafter set forth.

In the accompanying drawings, Figure 1 is a vertical section showing an embodiment of the improved fuel-feeding device in position for use. Fig. 2 is a section on the line *a b* of Fig. 1, and Fig. 3 is a side elevation of the improved stoker.

Referring to the drawings, the boiler *A* is suitably supported on a foundation *B*. Beneath the boiler is arranged the stoker *C*, extending over a grate *D*. The furnace of which the grate and stoker form a part will of course be provided with suitable ash-chambers and air-draft where necessary and connections whereby proper circulation of water and air may be effected. Only those portions of the last-mentioned devices are shown, however, which are necessary to an understanding of the present invention.

The grate *D* is rotatable by any suitable means. The stoker *C* extends radially over the grate and comprises a conveyer which may be a screw *29*, fitting within a tube or casing *30*, which communicates upon the outside of the furnace with a fuel-supply chute *31* and within the furnace with a chamber *32*, in which is rotatably mounted a feeder, preferably a fluted cone *33*, for feeding the fuel, the chamber *32* having openings *34* for the passage of said fuel. The shafts of the screw and cone are driven by any suitable means. (Not shown.)

The stoker is surrounded by a water-jacket *35*, through which extend passages *36* for the passage of the fuel. Preferably tubes *37* are secured to the wall of the chamber *32*, surrounding the holes therein and extending into the holes in the water-jacket to properly lead the fuel. The jacket may be fed by a water-pipe *50*, which may conveniently extend upwardly from the center of the grate, as shown. The water-jacket affords protection from the heat of the furnace to the working parts of the stoker, and the hot water may be employed for feeding the boiler, as

through a pipe *39*, connected to a hot-well, injector, or other boiler-feed source. A blow-off cock *40* near the bottom of the water-jacket should be provided. For securing greater structural strength and to prevent the blowing out of the end *51* of the water-jacket by the pressure in it, as by the generation of steam, rivets *52* are provided, which secure together the outside end *51* and the inside end *53* of the jacket.

The shaft *54* of the screw *29* is journaled in the ends of the screw-casing *30*. The shaft *55* of the cone *33* is journaled in projections from the casing *30*, which project into the chamber *32*, which is inclosed by the casing *56*. The casing *56* is supported from the casing *30*, which in turn is supported by means of lugs *57*, extending longitudinally thereof and engaging with brackets *58*, fixed to the interior of the water-jacket and extending longitudinally of the stoker. The casing *56* is adjustably connected with the casing *30*, as hereinafter described, so that the tubes *37* may be withdrawn from the passages *36* when desired. It will be obvious that the stoker parts are connected together to form a unit which is not in any way secured to the jacket or other portion of the furnace, but may be slid out longitudinally whenever required without disturbing the remainder of the structure. The space between the cone *33* and casing *56* may be varied in size by adjusting said casing, and thereby the amount of fuel adjacent each opening *34* can be controlled. The casing *56* is preferably adjustable at both ends, and in the embodiment of the invention illustrated it is supported at its outer end by a projection *60*, which rests upon a crank *61*, pivoted to the casing *30* at *62* and rotatable by means of an arm *63*, fixed to the crank *61* and pivoted to the slide *64*, which extends outwardly through the front face of the furnace. It will be seen that by pushing the slide *64* inwardly the crank will be moved to such position as to permit the projection, and with it the outer end of the casing *56*, to fall, thereby increasing the clearance between the casing and the cone and increasing the feed of fuel near the outer edge of the grate. Movement of the slide in the opposite direction will cause the crank to raise the outer end of the casing *56*, and thereby decrease the fuel-feed at that end.

The inner end of the casing is adjustable by means of a slide *65*, which operates by its reciprocation to raise and lower the inner end

of the casing through the crank 66, to which it is pivoted and which is in turn fixed to a shaft 67. To the shaft 67 is fixed a cam 68, which is inclosed by a strap 69, pivoted to the casing 56. The slides 64 and 65 may be provided with notches, as shown, which engage with a front plate 70 of the furnace to fix them in adjusted positions. The plate 70 is removable, so that the withdrawal of the 10 stoker, as before described, may be effected.

It is essential that fuel should be fed to every portion of the grate from the center to the outside, and for this reason the holes through which the fuel is fed from the stoker 15 are staggered, as shown.

It will be obvious from the location of the stoker that if it were not filled with coal gases would enter the fuel-feeding holes and might by their own heat or that generated 20 by coal, which might be ignited within the stoker-casing, cause the stoker to be damaged. This might readily occur if for any reason the supply of fuel suddenly ran out or the power should be disconnected from the 25 stoker, unless some means were employed to prevent it. This may be prevented by creating a fluid-pressure within the stoker, as by connecting the interior of the stoker-casing, by means of a pipe 71, with a source of steam 30 or compressed air. The supply of this fluid to the stoker may be controlled by any suitable means, as a valve 72. The entrance of furnace-fumes into the stoker may thus be prevented at all times.

35 While I have illustrated my invention in what I consider its best application, it is to be understood that it may have other embodiments without departing from its spirit. I do not, therefore, desire to be limited to the 40 precise construction shown.

Certain features of the construction hereinbefore described are disclosed in an application filed April 1, 1904, Serial No. 201,121.

What I claim is—

45 1. In a furnace, the combination with a rotatable grate, of a conveyer adapted to move fuel radially of said grate, and a rotatable cone arranged to carry fuel between said conveyer and grate, substantially as described.

50 2. In a furnace, the combination with a rotatable grate, of a conveyer adapted to move fuel radially of said grate, a fluted feeder arranged to carry fuel between the 55 conveyer and grate, and a water-jacket surrounding said conveyer and feeder, substantially as described.

60 3. In a furnace, the combination with a rotatable grate, of a conveyer adapted to move fuel radially of the grate, a rotatable cone arranged between and adapted to deliver fuel from the conveyer to the grate, and a water-jacket extending about said conveyer and cone, substantially as described.

65 4. In a furnace, the combination with a

rotatable grate, of a conveyer adapted to move fuel radially of the grate, and a fluted cone mounted to rotate between the conveyer and grate and to carry fuel from the conveyer to the grate, substantially as described.

5. The combination with a grate, of a stoker extending thereover and a water-jacket surrounding said stoker having openings through which fuel is fed to the grate, substantially as described.

6. In a furnace, the combination with a grate, of a conveyer adapted to move fuel toward the center of the grate, a water-jacket arranged above the grate into which 80 said conveyer extends, said jacket having a plurality of passages through which fuel may pass to the grate, and a feeder arranged between and adapted to carry fuel from the conveyer to said passages in the water- 85 jacket, substantially as described.

7. In a furnace, the combination with a rotatable grate, of a water-jacket extending radially of said grate and open at its outer end, said jacket having formed in its lower 90 wall passages through which fuel may pass to the grate, and a stoker adapted to be removably inserted in said jacket through the outer end thereof and comprising means for conducting fuel from outside of said jacket 95 to the fuel-passages in the lower side thereof, substantially as described.

8. In a furnace, the combination with a rotatable grate, of a casing supported above the grate, a water-jacket inclosing the inner 100 end of said casing and provided with passages through which fuel can pass to the grate, means for conveying fuel through said casing to said passages, and means arranged at the axis of the grate for supplying water to the 105 water-jacket, substantially as described.

9. In a furnace, the combination with a grate, of a water-jacket arranged above said grate, and having formed in its lower side 110 passages for conducting fuel to the grate, a casing adapted to be removably supported within said water-jacket, and having passages communicating with the fuel-passages in said jacket, and means within said casing for conveying fuel from the outer end thereof 115 to said fuel-passages, substantially as described.

10. The combination with a stoker having its parts so joined as to form a unit, of a water-jacket inclosing the stoker, said stoker as 120 a unit being detachably supported within said water-jacket, substantially as described.

11. The combination with a water-jacket having longitudinally-extending brackets on its interior, of a stoker inclosed by said 125 water-jacket and having longitudinally-extending projections resting upon said brackets.

12. In a furnace, the combination with a grate, of a conveyer adapted to positively 130

move fuel toward the center of said grate, a feeder mounted to rotate between and convey fuel from said conveyer to the grate, an apertured plate between the feeder and grate, and means for varying the distance between the feeder and the apertured plate, substantially as described.

13. In a furnace, the combination with a grate, of a conveyer adapted to move fuel toward the center of the grate, a feeder mounted to rotate between and carry fuel from the conveyer to the grate, an apertured plate between the feeder and grate, and means for independently adjusting either 15 end of the apertured plate relative to the feeder, substantially as described.

14. In a furnace, the combination with a

grate, of a conveyer adapted to move fuel toward the center of the grate, a feeder mounted to rotate between and carry fuel 20 from the conveyer to the grate, an apertured plate adjustably supported between the grate and feeder, and means extending beyond one end of the feeder for independently adjusting either end of said plate relatively 25 to the feeder, substantially as described.

In testimony whereof I have signed my name to this specification in the presence of two subscribing witnesses.

EMRO HARCHARICK.
